MECHANICAL TOY

Harry J. Chinn, 1709 Pensacola St.,
Honolulu, Hawaii 96822

Filed Aug. 15, 1966, Ser. No. 3,475

Term of patent 14 years

(Cl. D34—15)

FIGURE 1 is a side perspective view of the mechanical toy embodying my new design.

FIGURE 2 is a front elevation view of the mechanical toy.

FIGURE 3 is a right-side view of the mechanical toy.

FIGURE 4 is a rear elevation view of the mechanical toy.

FIGURE 5 is a bottom view of the mechanical toy.

For purposes of illustration, the reciprocable arms of the toy are shown in one extreme position in FIGURE 1, and in the other extreme position in FIGURES 2 through 4.

The drawing is lined for red, yellow, and green.
I claim:

The ornamental design for a mechanical toy, as shown and described.
